UNITED STATES PATENT OFFICE.

LEWIS T. HOUGHTON, OF WORCESTER, MASSACHUSETTS.

FASTENING DEVICE FOR RING-HOLDERS.

1,170,446.

Specification of Letters Patent.

Patented Feb. 1, 1916.

Application filed May 5, 1915. Serial No. 23,149.

To all whom it may concern:

Be it known that I, LEWIS T. HOUGHTON, a citizen of the United States, residing at Worcester, in the county of Worcester and State of Massachusetts, have invented a new and useful Fastening Device for Ring-Holders, of which the following is a specification.

This invention relates to a fastening device for ring holders and particularly to a device for detachably securing a ring holder upon the ring rail of a spinning or twisting frame.

A device for a similar purpose is shown in my prior Patent No. 990,360, issued April 15, 1911, my present invention being in the nature of an improvement over the device therein shown and described.

In my prior patent I have shown a ring holder which consists of a flat metal plate having upstanding ears for engaging the lower flange of a spinning or twisting ring and provided with segmental notches at opposite sides of its periphery. The fastening devices shown in the patent comprise a pair 25 of fastening clips each of which has a slotted base portion with an upwardly projecting flange at one end, the flange being curved to correspond to the outline of the segmental notches and being inclined 30 slightly outwardly from the perpendicular. After the clips have once been adjusted so as to bring the ring central with the spindle, one ring holder may be removed and a different holder may be snapped into place 35 without readjusting the clips, this being made possible by the slight resilience of the sheet metal clips and also of the ring holder. The yielding movement which can thus be secured is very slight and does not permit 40 any appreciable variation in the size of the ring holders.

Such variation however, is unavoidable in commercial manufacture, and it is the object of my present invention to improve the 45 construction above described by providing greater resilience in the plate engaging portion of one or both of the fastening clips.

With this object in view my invention relates to certain arrangements, and combinations of parts which will be hereinafter described and more particularly pointed out in the appended claims.

A preferred form of my invention is shown in the drawings in which—

55 Figure 1 is a plan view of a portion of a ring rail with a ring and holder secured

thereon by my improved fastening device; Fig. 2 is a vertical sectional view on an enlarged scale taken along the line 2—2 in Fig. 1; Fig. 3 is an enlarged top plan view 60 of one of the fastening clips shown in Fig. 1, with a portion of a ring holder shown adjacent thereto; Fig. 4 is a side elevation of the clip shown in Fig. 3, the view being taken in the direction of the arrow 4; Fig. 5 65 is a detail view of the resilient member or spring forming a part of the fastening clip shown in Fig. 3, and Fig. 6 is an enlarged sectional view taken along the line 6—6 in Fig. 1.

70 Referring to the drawings, I have shown a portion of a ring rail at 10 having a ring holder 11 mounted thereon and supporting a spinning or twisting ring 12 provided with the usual traveler 13. The ring holder comprises a single flat piece of sheet metal having oppositely-disposed upwardly-projecting ears 14 engaging and positioning the ring 12 and having the usual upwardly-projecting traveler clearer 15.

75 The fastening device for securing the ring holder to the ring rail comprises two adjustable clips 16 and 17. The clip 16 is shown in section on an enlarged scale in Fig. 6 and comprises an inverted cup-shaped member having its sides converging slightly toward the bottom and provided with an axial opening 18 through which extends a screw 19 by which it is secured to the rail 10. The opening 18 is of greater diameter than the 80 body of the screw 19, thus permitting limited adjustment of the clip upon the ring rail. After the clip is correctly positioned, it is 85 rigidly secured in place by tightening the screw 19.

90 The clip 17 is similar in general appearance to the clip 16 with the exception that the sides of the cup-shaped member or clip 17 are preferably cylindrical instead of converging. The clip 17 is provided with an 95 axial opening 20 corresponding to the opening 18 of the clip 16 and is secured in position by a fastening screw 21. The clip 17 is also provided with an additional opening or slot 22 in the side wall thereof through 100 which projects the narrowed portion 23 of a resilient member or spring 24. The main portion of the spring 24 is substantially circular in outline and fits closely within the cup-shaped portion of the clip 17. An opening in the spring is formed at one side thereof and the ends of the spring are normally 105 110

slightly separated as clearly shown in Figs. 3 and 5.

In positioning the ring holder upon the ring rail the screws 19 and 21 are left loose 5 until the ring holder and ring are accurately centered with relation to the spindle. The screws are then tightened, binding the clips in position with the upper portion of the clip 16 slightly overhanging the ring holder 10 and with the cylindrical portion of the clip 17 preventing lateral movement of the ring away from the clip 16. Vertical movement of the ring holder adjacent the clip 17 is prevented by the engagement of the projecting portion 23 of the spring 24 with the upper outer edge of the plate holder. While the spring 24 is primarily intended to force the plate downward against the rail, it may also exert a certain amount of side pressure 15 tending to move the plate laterally against the clip 16. When it is found desirable to change the size of the ring, the ring holder may be removed by forcing it upwardly adjacent the clip 17, the opening in the 20 spring 24 permitting the portion 23 thereof to be forced backwardly into the slot 22 as the ring holder moves upwardly. The new ring holder is inserted by placing one notch 25 in engagement with the fixed clip 16 and 30 forcing the opposite edge of the holder downwardly past the clip 17, compressing the spring 24 during such downward movement.

By the provision of the spring 24 it will 35 be seen that I have greatly increased the resiliency of my fastening device, thus permitting reasonable variation in the diameter of the ring holders without necessitating readjustment of the fastening clips. In 40 stead of using the rigid clip 16 I may use two of the clips 17 each containing a resilient holder-engaging member. Under ordinary conditions, however, I prefer to use one rigid clip and one yielding clip as shown 45 in the drawing.

Having thus described my invention it will be evident that changes and modifications can be made therein by those skilled in the art without departing from the spirit 50 and scope thereof as set forth in the claims and I do not wish to be otherwise limited to the details herein disclosed, but

What I do claim is:—

1. In a ring frame, in combination, a ring, 55 a holder for said ring having notches in its flat outer edge portion, a ring rail, and means to detachably secure said holder to said rail, said means comprising a pair of clips adjustably fixed to said rail and en-

gaging the notches in said holder to position the holder upon the rail, one of said clips containing a separate resilient member adapted to yield relatively to its clip to a substantial extent as the holder is placed in position between the clips and said resilient member thereafter engaging said holder and co-operating with said clips to retain said holder in position. 60

2. In a ring frame, in combination, a ring, 70 a holder for said ring having notches in its flat outer edge portion, a ring rail, and means to detachably secure said holder to said rail, said means comprising a pair of clips adjustably fixed to said rail and engaging the notches in said holder to position the holder upon the rail, one of said clips containing a separate resilient member 75 effective to engage the upper outer edge of said holder and to force the holder laterally against the opposite clip and also downwardly against the ring rail. 80

3. In a ring frame, in combination, a ring, 85 a holder for said ring, a ring rail, and means to detachably secure said holder to said rail, said means comprising a pair of clips adjustably fixed to said rail and engaging notches in said holder to position the holder upon the rail, one of said clips having an 90 opening in one side thereof and containing a resilient member having a portion normally projecting outwardly through said opening, said member being adapted to yield to permit the movement of a ring holder upwardly or downwardly adjacent said clip and past said opening. 95

4. In a ring frame, in combination, a ring, a holder for said ring, a ring rail, and means to detachably secure said holder to said rail, said means comprising an inverted cup-shaped clip having a downwardly and inwardly converging flange, said clip being adjustably fixed to said rail and engaging a notch in said holder, a second cup-shaped clip having a downwardly extending substantially cylindrical flange with an opening 105 in one side thereof, said second clip being adjustably fixed to said rail and engaging a second notch in said holder, and a substantially circular spring fitting within said cylindrical flange, said spring having an 110 opening between the ends thereof within the clip and having a narrowed portion projecting outwardly through the opening in said flange in position to yieldingly engage the upper outer edge of said holder. 115

In testimony whereof I have hereunto set my hand.

LEWIS T. HOUGHTON.
